(57) **CLAIM**

The ornamental design for a toiletry/clothespin bag, as shown and described.

DESCRIPTION

FIG. 1 is a front perspective view of a first embodiment of a toiletry/clothespin bag, in accordance with my new design.

FIG. 2 is a front perspective view of the first embodiment of the toiletry/clothespin bag with the top portion unzipped to show the interior, in accordance with my new design.

FIG. 3 is a rear perspective view of the first embodiment of the toiletry/clothespin bag, in accordance with my new design.

FIG. 4 is a front view of the first embodiment of the toiletry/clothespin bag, in accordance with my new design.

FIG. 5 is a rear view of the first embodiment of the toiletry/clothespin bag, in accordance with my new design.

FIG. 6 is a left side view of the first embodiment of the toiletry/clothespin bag, in accordance with my new design.

FIG. 7 is a right side view of the first embodiment of the toiletry/clothespin bag, in accordance with my new design.

FIG. 8 is a top view of the first embodiment of the toiletry/clothespin bag, in accordance with my new design.

FIG. 9 is a bottom view of the first embodiment of the toiletry/clothespin bag, in accordance with my new design.

FIG. 10 is a rear view of the first embodiment of the toiletry/clothespin bag having optional suction cups, in accordance with my new design.

FIG. 11 is a front perspective view of a second embodiment of a toiletry/clothespin bag, in accordance with my new design.

FIG. 12 is a front view of the second embodiment of the toiletry/clothespin bag, in accordance with my new design.

FIG. 13 is a rear view of the second embodiment of the toiletry/clothespin bag, in accordance with my new design.

FIG. 14 is a left side view of the second embodiment of the toiletry/clothespin bag, in accordance with my new design.

FIG. 15 is a right side view of the second embodiment of the toiletry/clothespin bag, in accordance with my new design.

FIG. 16 is a top view of the second embodiment of the toiletry/clothespin bag, in accordance with my new design; and,

FIG. 17 is a bottom view of the second embodiment of the toiletry/clothespin bag showing an optional waist strap and mesh bottom, in accordance with my new design.

In the drawings, the broken lines indicate portions of the article not claimed or the unclaimed environment and form no part of the claimed design.
